UNITED STATES PATENT OFFICE.

HENRY E. RICHARDS, OF OTTAWA, ILLINOIS.

DOOR-HANGER.

SPECIFICATION forming part of Letters Patent No. 241,882, dated May 24, 1881.

Application filed October 23, 1880. (Model.)

To all whom it may concern:

Be it known that I, HENRY E. RICHARDS, of Ottawa, in the county of La Salle and State of Illinois, have invented a new and valuable Improvement in Parlor-Door Hangers; and I do hereby declare that the following is a full, clear, and exact description of the construction and operation of the same, reference being had to the annexed drawings, making a part of this specification, and to the letters and figures of reference marked thereon.

Figure 1 of the drawings is a vertical section. Figs. 2, 3, 4, 5, and 6 are details.

This invention relates to devices for operating doors; and it consists in the construction hereinafter specified.

In the annexed drawings, A is the studding, B the track-supports, and C the tracks.

D is a roller composed of two portions, b, connected by an axle, b', the portions b being preferably flanged and having a rubber band around their peripheries.

Projecting up through slot E, between the tracks C, is a rider-bar, F, whose upper bar, f, passes over axle b'. This rider-bar F is composed of a strong metal loop having an upper portion or bar, f, side arms, f' f', the curved bearings e e, and a lower bar, f², having slides n n.

H represents a door, to the upper edge of which is fastened a plate, I, having slots i and projecting ridges i' i', with a recess between

them. At one end of plate I is a lug, i², through which passes a set-screw, H', engaging a lug, f³, upon rider-bar F.

G is an adjustable bearing made fast to bar f of rider-bar F.

The plate I is made fast to the top of the door. Rollers D are put in place with their rider-bars projecting down through slot E. The slides n n of the rider-bar are slipped into slots i i, and the rider-bar is made fast by screw H'. In case the door should sag or droop at one end it may be lifted or leveled by means of the set-screw H'.

I claim—

1. The combination of door H, plate I, having slots i i, rider-bar F, having slides n n, and set-screw H', substantially as and for the purposes set forth.

2. The combination of the tracks C, roller D, composed of two portions, b b, connected by an axle, b', rider-bar F, having bearings e e, slides n n, and lug f³, plate I, having slots i i and lug i², set-screw H', and a door, H, substantially as and for the purposes set forth.

In testimony that I claim the above I have hereunto subscribed my name in the presence of two witnesses.

HENRY EUGENE RICHARDS.
